UNITED STATES PATENT OFFICE.

GEORGE C. GARDNER AND JAMES A. GROW, OF RICHMOND, VIRGINIA, ASSIGNEES TO THE TREDEGAR COMPANY, OF RICHMOND, VIRGINIA, A CORPORATION OF VIRGINIA.

ENGINE-LATHE.

1,139,026.

Specification of Letters Patent. Patented May 11, 1915.

Application filed January 6, 1915. Serial No. 851.

To all whom it may concern:

Be it known that we, GEORGE C. GARDNER and JAMES A. GROW, both citizens of the United States, residing at Richmond, in 5 the county of Henrico and State of Virginia, have invented certain new and useful Improvements in Engine-Lathes, of which the following is a specification.

Our invention relates more particularly 10 to attachments for engine lathes, but in order that our improvements may be fully understood we have shown in the accompanying drawings parts of an engine lathe of ordinary construction, slightly modified, 15 and with our improvements applied.

Our invention relates particularly to engine lathes of the class in which the work 20 is carried by the rotary member of a head-stock and the tool is attached to a tool-holder mounted on a support in turn mounted on a carriage which is movable longitudinally of the lathe and in which lathe while the tool-holder does not rotate it is fed with the carriage toward the work at the required speed. 25

Heretofore the longitudinal movement of the tool-holder toward and from the work has generally been effected by moving the tool-carriage to which the tool is rigidly secured toward and from the head-stock either by means of a pinion on the carriage 30 engaging a rack on the lathe-bed or by a nut on the carriage engaging a longitudinal lead screw.

According to our invention we provide a lathe which may be operated and adjusted in the usual way and in which also provision is made by means of which the feed or longitudinal movement of the tool-carriage 35 may be effected by moving the carriage and tool-holder by means of the lead screw and certain novel connections between the lead screw and the tool-holder, in which case the nut usually employed for connecting the 40 carriage with the lead screw is thrown out of operation.

We would have it understood, however, 50 that our invention consists mainly in an attachment which may be applied to lathes of all standard makes.

In the accompanying drawings: Figure 1 shows a side elevation of so much of an engine lathe with our improvements applied as is necessary to show our invention. Fig. 55 2 is a detail view, in section, showing parts

of the connections between the lead screw and our improved attachment. Fig. 3 is a detail view, in section, and on an enlarged scale, showing the mechanism for moving the carriage longitudinally on the lathe-bed by means of rack and pinion mechanism. Fig. 4 is a detail view, on an enlarged scale and in longitudinal section, showing particularly part of the mechanism connecting the tool-holder with the lead screw. Fig. 5 is a view on an enlarged scale, and in rear end elevation, of the lathe shown in Fig. 1, the lead screw being shown in transverse section. Figs. 6 and 7 are also on an enlarged scale. Fig. 6 shows an end elevation of the hand-wheel for operating the half nuts, which latter are shown in dotted lines. Fig. 7 is a detail view in section, showing more particularly the connections between the hand-wheel and the half nuts. Fig. 8 is a detail view, on an enlarged scale, and in side section, showing how our improvements may be applied to a turret lathe. Fig. 9 shows a plan view thereof. Fig. 10 is a detail view in section, showing the connections between the screw, forming part of our invention, and the tool-holder or boring bar. Fig. 11 is a detail view, showing other features of such connection. Fig. 12 illustrates another way of connecting said screw with the boring bar or tool-holder. Fig. 13 is a detail view, partly in side elevation and partly in section, showing a thrust bearing which is applied to the head-stock of the lathe. 90

As before stated, our invention contemplates very little change in the lathe proper, but in order that our improvements may be fully understood we will describe in a general way the general characteristics of the lathe shown and will indicate how our improvements are applied thereto and used in connection therewith. 95

The lathe-bed A supports the head-stock and the tail-stock in the usual way. B indicates the rotary part of the head-stock and to this rotary part B the work X is attached in the usual way. C indicates a support for the work which is also of usual construction. 100

The lathe-carriage D may be provided with the usual mechanism for adjusting it, and a pinion E is adapted to engage a longitudinal rack F on the lathe-bed, which pinion may be operated either by hand or by 110

power and may be moved into and out of engagement with the rack. Fig. 3 shows mechanism which may be employed for this purpose. As there shown the pinion E, 5 which engages the rack F, is formed on a stem e having a reduced inner end e' supported on a bracket e², and a forward portion carrying at its outer end a knob or handle e³. On the stem e is mounted a spur 10 wheel E' which engages a pinion E² operated by a hand-wheel E³ (Fig. 1). The hub of the wheel E' is connected with the stem e by a feather, as shown, and a spring detent e⁴ is adapted to engage recesses e⁵, e⁶ in the 15 stem. By this means the pinion E may be moved into and out of engagement with the rack F and held in either the engaged or disengaged position. All of such mechanism is of usual construction.

20 G indicates the usual lead screw, operated in the usual way to feed the carriage with the tool thereon toward and from the work.

We have indicated at G' the mechanism 25 for connecting and disconnecting the lead screw with the carriage. The tool-holder H (which is also called the boring bar) is mounted on a suitable support H' on the tool-carriage. A rigid connection is made 30 between the support H' and the tool-holder.

35 As shown the reduced rear portion of the tool-holder lies in a block h², forming part of the support H'; and said tool-holder is rigidly connected with said support by a cap h which is bolted down to the support.

40 Preferably the cap is connected with the tool-holder by groove-and-feather connection h³ which will prevent the tool-holder from turning about its axis while at work. It will be understood, however, that there is 45 no longitudinal movement of the tool-holder relatively to its support H'.

To the rear end of the tool-holder H is 50 connected a screw I which extends into the tail-stock B' of the lathe and through a sleeve J, having a shoulder j which rests against the tail stock and provides the rear-end thrust bearing of the mechanism. This sleeve J forms a bearing support for the rear portion of the screw I and this screw also extends through a sleeve K to which is keyed at h a worm wheel L between which and the sleeve J is interposed a bearing collar M.

55 N indicates an annular hand-wheel surrounding the screw I and receiving a collar O on which the hand-wheel is free to rotate. Between the hand-wheel and collar and the sleeve K are interposed half nuts P which are pivoted on rods Q, shouldered at q, q' and tapped into the sleeve K. These rods 60 extend through the collar O and carry nuts q². By reason of the shoulders q, q' the hand-wheel and collar are held a sufficient distance from the sleeve K to allow the half nuts to move freely.

65 The worm-wheel L engages a worm r on

an inclined shaft R mounted in suitable bearings on a frame S. The lower end of the shaft R carries a worm-wheel T which engages a worm T' keyed to the lead screw G, as indicated particularly in Fig. 2. 70 When the half nuts engage the screw I and the lead screw is rotated an endwise movement is given to the screw I and to the tool-holder H, connected therewith, the carriage D of course moving with the tool-holder. 75 Each half nut P is formed with a lug p, adapted to engage a lug n on the hand-wheel N. As clearly shown in Figs. 6 and 7 there are two lugs n and these are adapted to engage the lugs p and open and close the half 80 nuts. It will be observed that the shaft R has two bearings brackets r', r² at its upper end. The shaft I has a left-hand screw and the arrangement is such that the thrust on the shaft R is downward, causing the 85 worm-wheel r to bear against the lower bracket r' which is firmly secured to the frame S.

In order that the half nuts P shall properly engage the screw I, they should be 90 threaded, as shown in Fig. 4, and should engage the screw as there shown. This, however, cannot be effected unless the threads in the nuts are properly positioned to receive the threads of the screw, and in order that 95 this may be accomplished the connection between the front end of the screw I and the tool-holder is made adjustable, in the manner indicated particularly in Figs. 10 and 11. As there shown the screw I extends into 100 a recess in the rear end of the tool-holder and it is provided with an annular groove i, into which projects a pin i' carried by the tool-holder. This arrangement permits the screw to revolve or turn relatively to the 105 tool-holder but prevents its endwise withdrawal therefrom.

I' indicates a hand-wheel which is connected to the screw by a key i², so that when the hand-wheel is turned the screw is also 110 turned.

i³ indicates a spring pawl carried by the hub of the hand-wheel and which is adapted to engage recesses x formed in the end of the tool-holder. The arrangement is such that 115 when the wheel I' is turned in one direction the pawl i³ engages one of the recesses and the wheel, screw and tool-holder are locked together, but if the wheel I' be turned in the opposite direction it will be disengaged from the tool-holder and a sufficient movement about its axis may be given to the screw shaft I to bring its threads into proper relation with the recesses of the half nuts so that the latter may be made to properly engage 120 the screw and to thus provide a driving connection between the nuts and the screw which will move the screw and the tool-holder connected therewith toward the work. 125

In Fig. 12 we have shown a modified way 130

of connecting the screw shaft I with the tool-holder. Instead of forming the recesses *x* in the tool-holder and instead of boring the tool-holder to receive the end of the shaft, we provide a sleeve *I*² which is threaded at *b'* and engages a thread *b* cut on the reduced rear end of the tool-holder. Recesses *x* are cut into the rear or outer end of the sleeve *I*² to receive the spring pawl *i*³ of the wheel *I'*. The screw shaft is formed at its front end with a head *b*² which is adapted to enter the sleeve *I*² and bear against the shoulders *b*³ thereof. As before stated the end thrust at the tail-stock is taken by the bearing collar M inasmuch as the rearward thrust of the spindle I is communicated to the sleeve K through the nuts P and the worm wheel L bears against said collar. In order to take the end thrust at the head-stock we preferably equip the latter with the devices shown in Fig. 13. In this figure U indicates a part of the frame of the head-stock and V indicates a sleeve forming part of the rotary portion of the head-stock. This sleeve V, shown in Fig. 13, is also indicated in Fig. 1. A bearing block V' is supported on a suitable frame W attached to the frame U and this bearing block receives a ball *w* attached to the sleeve V. By this mechanism, when the operation of boring is being performed the end thrust is received at both ends of the lathe in such manner as to take the strain from other portions thereof. When the half nuts P are disengaged from the screw I the carriage D may be moved back and forth longitudinally by means of the pinion E. This may be readily disengaged, when the desired adjustment is given to the carriage and then the lead screw G may be connected with the carriage by means of the devices G' and the lathe may then be operated in the usual way as in other lathes, the carriage being equipped with a suitable tool-holder. But when the half nuts are made to engage the screw I the latter will operate in the manner before described in accordance with our invention. It will thus be understood that the carriage may be adjusted and fed back and forth by means of the rack and pinion mechanism and by means of the lead screw, or these may be thrown out of operation and the carriage and tool-holder may be operated or fed toward the work in accordance with our invention.

Our invention is especially useful for rough boring cast iron or bar stock steel to convert it into bushing form. Finer boring may be effected by other mechanism. Our improvements may be applied to a turret lathe in the manner indicated in Figs. 8 and 9. As there shown the circular top plate Y of the turret is pivotally connected with supporting blocks Y', Y² by means of a pivot bolt *y*. To this pivot bolt is con-

nected a casting *y'*, in turn connected with the screw shaft I, hereinbefore referred to.

H indicates a tool-holder or boring bar of the kind hereinbefore described.

*h*⁴ indicates lubricating devices therefor. 70 The tool-holder is supported in a frame A² which also carries an adjustable tool-holder a. The arrangement is such that the circular top plate Y may be turned so as to bring either the tool holder H or tool-holder 75 a into line with the work. In either case the projection *y*² of the casting *y'* will bear against the tool-holder and feed it toward the work.

We claim as our invention: 80

1. An attachment for engine lathes, comprising a supporting frame, a shaft carried thereby and provided with means for connecting it with the lead screw of the lathe, a screw shaft adapted to be connected with the 85 tool-holder of the lathe, and connections between said first-mentioned shaft and said screw shaft.

2. An attachment for engine lathes, comprising a supporting frame, a shaft carried 90 thereby and provided with means for operatively connecting it with the lead screw of the lathe, a screw shaft adapted to be connected with the tool-holder of the lathe, a sleeve surrounding said screw shaft and 95 geared to said first-mentioned shaft, half nuts engaging said screw shaft, and a hand-wheel connected with said half nuts for opening and closing them.

3. An attachment for engine lathes, comprising a supporting frame, a shaft carried 100 thereby and provided with means for operatively connecting it with the lead screw of the lathe, a screw shaft adapted to be connected with the tool-holder of the lathe, 105 a hand-wheel carried by said screw shaft and provided with a pawl adapted to engage the tool-holder, and connections between said first-mentioned shaft and said screw shaft. 110

4. The combination with the head-stock and tail-stock of an engine lathe of a rotary spindle adapted to be connected with the work, an end thrust bearing for said spindle, a tool-holder or boring bar supported on the lathe carriage, a screw shaft connected with said boring bar and extending into the tail-stock, a sleeve surrounding said screw shaft and carrying a worm wheel, an end thrust bearing interposed between the 120 tail-stock and said sleeve and worm wheel, means for connecting said sleeve with the screw shaft and for disconnecting it therefrom, and connections between said worm wheel and the lead screw of the lathe. 125

5. An engine lathe, comprising a carriage, a rack, and a lead screw, means for connecting the carriage with the lead screw and for disconnecting it therefrom, a pinion mounted on the carriage and adapted to be con- 130

nected with the rack and to be disconnected therefrom, a tool-holder, a support on the carriage to which the tool-holder is secured, a screw shaft connected with the tool-holder and extending into the tail-stock of the lathe, driving connections between said screw shaft and the lead screw of the lathe, and means for connecting the screw shaft with said driving connections and for disconnecting it therefrom.

6. The combination in an engine lathe of a tool-holder, a lead screw, a carriage, means for connecting the carriage with the lead screw and for disconnecting it therefrom, a

screw shaft, driving connections between the screw shaft and the lead screw, a hand-wheel on the screw shaft, and means carried by the hand-wheel for connecting it with the tool-holder to hold the screw shaft against rotation relatively to the tool-holder.

In testimony whereof, we have hereunto subscribed our names.

GEORGE C. GARDNER.
JAMES A. GROW.
